IRON REST FOR IRONING BOARDS

Allan B. Sterner, Cos Cob, Conn.

Application March 13, 1950, Serial No. 149,350

2 Claims. (Cl. 248—117.4)

1

This invention relates to an iron rest for ironing boards adapted for supporting an electric or other iron when not in actual use.

An object of the invention is to provide a novel and simple iron rest adapted to support an iron horizontally on the flat bottom thereof and which is provided with means to detachably engage and clamp the rest to the board at an edge thereof to support the iron over the ironing surface of the board.

Another object is to provide an iron rest comprising a plate shaped like the contour of the iron to support the iron thereon and having means to retain the iron and preclude slipping thereof off of the rest, and means at the bottom of the plate to clip the same to an edge of an ironing board in supporting position.

A still further object is to provide an iron rest of simple and economical construction embodying an iron rest plate to receive the iron thereon above the board and covering thereof and a spring clamp at the bottom of the plate to engage over the edge of the board and hold the rest plate in position as well as to dissipate the heat transferred to the plate from the hot iron and prevent scorching of the ironing board covering.

With the above and other objects in view that will become apparent as the nature of the invention is better understood, the same consists in the novel form, combination and arrangement of parts hereinafter more fully described, shown in the accompanying drawing, and claimed.

In the drawing:

Figure 1 is a top plan view of an iron rest embodying the invention in applied position for use.

Figure 2 is a side elevation of the rest as seen in Figure 1, and

Figure 3 is a bottom plan view of the rest.

Referring to the drawings in detail, the present iron rest comprises a flat plate 10 of suitable metal or plastic of the same shape as the flat bottom ironing surface of the iron to be supported. Plate 10 is provided with a surrounding marginal upturned rim flange 11 within which the iron is adapted to rest on the plate 10. The flange 11 forms a retaining shoulder to keep the iron on the rest plate and preclude slipping thereof off of the rest.

The rest plate 10 may be pressed, molded or stamped from a single blank with the iron retaining shoulder forming flange 11 preferably directed upwardly and outwardly at a slight angle obtuse to the plane of the plate. As indicated, the flange is relatively shallow or narrow with convexly curved sides 12 converging to a point 13 at the

2

apex or pointed end of the plate as with an iron. The rear wide edge portion 14 at the base end for the iron meets the convex sides 12 at the corners 15 forming a continuous stop flange around the entire edge of the plate to keep the iron in position thereon when at rest.

In order to detachably engage and clamp the rest to the board and covering thereof indicated by the phantom lines B in Figures 1, 2, and 4 of the drawings, a spring clamp 16 is fixed on the bottom of the plate 10 (centrally of the area thereof). This clamp is formed from a second simple plate blank of springy metal or plastic stamped out to form a bracket portion 17 and a spring 15 clamping jaw 18. Bracket portion 17 consists of a flat jaw-forming body with a convex side edge 19 and its ends bifurcated with V-shaped recesses 20 to form pairs of tapered legs 21 at each end. These legs are each bent up from the body substantially at right angles but slightly outwardly at their end portions as at 22 and then outwardly as at 23 to form attaching feet 24 offset from the body plate in alignment in the same horizontal plane parallel to the body and plate 10 to which they are fixed, to dispose the plate in spaced parallel relation to the body. This attachment may be effected by spot welds 25 for metal, or may be riveted, fused, or otherwise fastened for metal or plastic with flat and preferably countersunk heads where rivets or the like are used so that the top surface of plate 10 on which the iron rests is perfectly smooth and flat to prevent marring the ironing surface of the iron.

35 The other side edge of the body 17 is formed centrally with a reduced lateral extension 26 projecting out a slight distance in the plane of body and then bent down on itself at right angles thereto as at 27 to form an intermediate bight portion 28, in line with one side edge of plate 10, forming a closed end for the clamp 16 and to stand the device on edge in connection with the plate when not in use. The remaining end portion is again bent inwardly at right angles to bight portion 28 as at 29 to form the spring clamping jaw 18 in spaced substantially parallel relation to plate 18 and body of the bracket. Jaw 18 is bowed upwardly from end to end to effect easy application over an edge of the covered ironing board B and tightly grip the same without damaging the fabric covering.

In use, the clamp is applied to a side or end edge of the board as shown in the drawings with the body of bracket 10 at the top and jaw 18 at the bottom to firmly and detachably clamp the

board between said jaw and the body of the bracket. This disposes the rest plate 10 in spaced parallel relation to and above the body and top of the board B. In this position air circulates around the hot rest plate 10 which is heated by the hot iron thereon between ironings, and this tends to prevent overheating of the rest supplemented by the dissipation of the heat through and from the bracket and clamp jaw. The iron rests on the plate 10 and is retained from slipping off by the stop flange 11. The device may rest on bight 28 and edge of plate 10 on the board or other support against a wall when not in use, or left clamped to the board at one side or the end edge thereof.

Several important advantages result from the disclosed assemblage. For instance, the invention follows the general practice of having the iron pointed in contour in the advance zone of its direction of length and blunt in its trailing zone, but unlike the general practice of locating the structure for removably securing the rest assemblage onto the ironing board as secured to the blunt end zone of the rest member (and thus projecting in the general direction of length of such rest member), the supporting formation of the present invention is positioned on the rest member in such manner that the weight factor of the positioned iron is distributed over the rest member with respect to the direction of length of the iron, the supporting formation being spaced from both the pointed and the blunt end zones of the iron, the body zone of such formation extending transversely of the rest member approximately in the mid-zone of the length, being sufficiently displaced rearward from the exact mid point as to compensate for the difference in the weight conditions produced by the pointed and blunt end conditions. While this symmetry is varied in the transverse direction, the variation does not affect the weight disposition, since the body zone 19 and the fingers 21 all lie in a common plane which is also the plane of the top of the ironing board, thus providing for the symmetrical distribution of the weight of the iron.

This condition, plus the shaping of the finger zones 21, provides a second advantage through the extension of the finger characteristic into the upstanding areas of the formation and are then bent outward, as at 24 to form the finger end zones or the equivalent of spaced feet for securing the formation to the rest member 10, this arrangement being duplicated on the opposite sides of the body zone. Hence, the only actual contact between member 10 and the supporting formation is provided by these feet 24, and since they are spaced material distances apart and each is of fairly small extent, the heat of the feet developed through such contact, will be quickly dissipated due to the spacing provided by the upstanding areas of the finger zone, each of which is of a vertical length such as to provide the desired distance factor between the lower plane of the rest member and the top plane of the supporting formation body zone and within which space free circulation of air is possible to thereby provide for rapidity in dissipation of the heat, thus protecting the top surface of the ironing board. The distance factor between such planes is not sufficiently large as to render the positioned iron top-heavy, but is sufficient to assure rapid heat dissipation between the planes, especially in view of the extensive range of the formation both longitudinally and transversely

of the rest member that is produced by the particular arrangement of the body zone and the finger zones shown in the drawings and which places the major areas of the rest member and formation as located in such planes with the formation portions which connect such planes being of minimum areal extent and thus capable of rapid heat dissipation.

Another important advantage is due to extending the clamp transversely of direction of length of the rest member in contrast with the usual practice of extending it in accord with such direction of length—with the latter the blunt end of the iron becomes the outer end of the positioned iron; while there is no difficulty in mounting the rest member on either the near or the far side of the ironing board as well as the end of the board with either type of rest member, the effect of such mounting differs in the two types. With the standard type the direction of length of the iron extends perpendicular to the length dimension of the edge of the board to which the rest member is secured; this permits ready positioning of the iron for its resting location both at the end of the board and on the near side of the board, but renders iron manipulation wholly unsatisfactory when the rest is located at the far side, since the pointed end of the iron is then directed toward the user and thus very inconvenient while the iron is being placed in position or removed for service.

This difficulty is avoided with the arrangement of the clamping zone as extending transverse to the direction of length of the iron, this change in direction placing the direction of length of the iron as parallel with the edge of the ironing board to which the rest member is secured, instead of normal or perpendicular to such direction; as a result of this change the rest member can be conveniently located on either the near or the far side of the board or at the end, with the iron properly and efficiently manipulated in either of such positions.

From the above detailed description of the invention, it is believed that the construction, use, and operation thereof will at once be apparent, and while there is herein shown and described the preferred embodiment of the invention, it is nevertheless to be understood that minor changes may be made therein without departing from the spirit and scope of the invention as claimed.

I claim:

1. A removable iron rest for ironing boards comprising a horizontally extending iron-receiving sheet metal member having its upper and lower faces contoured to approximate the contour of the bottom face of an iron, said member having an upstanding marginal periphery of outwardly flaring type, and a sheet metal supporting formation therefor anchored to the lower face of the member, said formation including an element contoured to present a body portion having a finger portion on each of opposite sides of the body portion and with each finger including an upstanding part and an end part positioned beyond the upstanding part and bent outwardly to extend parallel with and be in secured relation with the lower face of the member, said upstanding part being dimensioned to produce a spaced relation of material extent between the plane of said formation body portion and the under side of the lower face of the member to form an open heat-dissipating spacing between said member and the body portion of the formation, said body portion projecting laterally beyond the adjacent

finger portions and being bent downwardly and then in return direction transversely of said member to form an ironing board engaging element for removably securing the iron rest to the ironing board.

2. An iron rest as in claim 1 characterized in that the body portion of the supporting formation extends transversely of the member and occupies a mid position with respect thereto in the formation, the finger portions of the formation projecting beyond such body portion and each being recessed toward the body portion with the recess of taper shape, each finger being completed by the upstanding part and the bent end part therebeyond adapted to be secured to the lower face of the rest member to thereby limit the contact between member and formation to

the spaced finger end parts and provide freedom of air circulation between the respective lower face of the rest member and such body portion of the formation and increase rapidity of heat dissipation for ironing board protection.
